UNITED STATES PATENT OFFICE.

JOHN L. C. CRONYN, OF BUFFALO, NEW YORK.

CIGAR-HOLDER.

SPECIFICATION forming part of Letters Patent No. 319,886, dated June 9, 1885.

Application filed October 27, 1884. (No model.)

To all whom it may concern:

Be it known that I, JOHN L. C. CRONYN, of the city of Buffalo, in the county of Erie and State of New York, have invented new and useful Improvements in Cigar-Holders, of which the following is a specification.

This invention relates to an improvement in that class of cigar mouth-pieces or holders in which the liquid or condensed vapor is retained in the holder and prevented from being drawn into the mouth by an inner tube extending rearwardly from the mouth-piece, and forming a collecting-chamber between the inner tube and the outer portion or body of the mouth-piece.

The object of my invention is to construct a mouth-piece or holder of this class of rubber or other elastic material, which will be light and convenient in use.

20 My invention consists in the improvement in the construction of the holder, which will be hereinafter fully set forth, and pointed out in the claim.

In the accompanying drawings, Figure 1 represents a sectional elevation, and Fig. 2 a side elevation, of my improved cigar-holder.

Like letters of reference refer to like parts in the several figures.

25 A represents the body of a cigar mouth-piece or holder, made of soft rubber in the usual form, and having its large portion *a*, preferably provided with openings *a'*, for ventilating the holder.

b represents the mouth-piece of the holder, 30 which is doubled back inwardly, so as to form

an inner tube, *c*, which projects inwardly or rearwardly from the mouth-piece *b*, but not far enough to reach the end of the cigar.

e is an annular chamber or space, which is formed between the tube *c* and the outer portion of the mouth-piece *b*, and which constitutes a receptacle for the vapor which condenses in the holder. The tube *c* prevents this noxious liquid from being drawn into the mouth with the smoke, as the liquid will adhere to the outer walls of the mouth-piece and be retained in the space *e*, between the outer wall and the inner tube, *c*. The tube *c* is made in one piece with the holder, and the latter is constructed of soft rubber of sufficient firmness to cause the holder to retain its shape, but sufficient flexibility to yield to the pressure of the teeth and lips, thereby forming a very convenient and agreeable holder.

I claim as my invention—

55 A cigar-holder constructed of flexible material, and composed of an outer body, *A*, and an inner tube, *c*, both the body and tube being formed of a single tubular piece of practically uniform thickness of material, and said tube 60 being doubled back into the body to extend rearwardly from the mouth-piece and form a collecting-chamber, *e*, with the body *A*, substantially as set forth.

Witness my hand this 14th day of October, 65 1884.

JOHN L. C. CRONYN.
